UNITED STATES PATENT OFFICE.

HARALD NIELSEN, OF MIDDLESEX, AND FREDERICK DEACON MARSHALL, OF WEST-MINSTER, LONDON, ENGLAND.

ROTARY GRATE FOR GAS-PRODUCERS.

1,378,369.

Specification of Letters Patent. Patented May 17, 1921.

Application filed September 11, 1920. Serial No. 409,665.

To all whom it may concern:

Be it known that we, HARALD NIELSEN, a subject of the King of Denmark, and FREDERICK DEACON MARSHALL, subject of the 5 King of Great Britain, residing at, respectively, 13 Firs avenue, Muswell Hill, Middlesex, England, and 19 Queen Anne's Chambers, Westminster, London, England, have invented new and useful Improvements 10 in Rotary Grates for Gas-Producers, of which the following is a specification.

Our invention relates to rotary grates for gas producers of the kind having a conical blast distributor formed in several steps or 15 layers with apertures for the distribution of the blast, a revolving water-sealed ash pan supported on wheels or rollers, a blast pipe in the center of the said ash pan and means for keeping the fuel in a state of continual 20 irregular movement and in a loose condition.

According to the invention the improved rotary grate consists of two or more superimposed flat sections of suitable material provided with openings for the admission 25 of the blast to the fuel and protecting lips which prevent the fuel from entering the interior of the sections. The said sections are preferably circular or polygonal in cross section and they gradually increase in diameter from the top downward to the bottom 30 of the producer, advantageously in such a manner that they inclose a cone the shape of which closely approaches that of the top of the fuel bed thereby preventing the blast 35 short circuiting during its passage through the same, as this generally takes place in other producers provided with a conical blast distributor and a fuel-bed the top of which closely approaches the horizontal.

40 The grate comprising a plurality of sections is preferably supported upon a blast distribution box, which is in turn supported by a revolving ash pan, and may form an integral part of the latter. I prefer to arrange 45 the separate grate sections eccentrically with respect to each other and to the center line of the producer, as indicated in Fig. 2 of the accompanying drawings.

With this construction it will be understood 50 that as the grate revolves, a lateral displacement of the fuel between or opposite each pair of grate sections is effected whereby any consolidation of clinkers is effectually prevented, and the fuel in proximity to the 55 sections is maintained in a loose condition,

thereby greatly facilitating the passage of the blast.

The blast distribution box into which the blast pipe enters through a stuffing-box is preferably provided with external helically arranged ribs in order to facilitate the downward movement of the ashes and is preferably mounted on a supporting ring of such height that the blast cannot be cooled by the contact of the walls of the distribution box 60 with water or water cooled ashes near the bottom of the pan.

To enable the invention to be fully understood we will describe it by reference to the accompanying drawing, in which:—

Figure 1 is a sectional elevation of the lower part of a gas producer fitted with the improved form of grate and

Fig. 2 is a plan thereof.

As shown in the accompanying drawing, 75 the rotary grate comprises a plurality of superimposed sections of different diameters. Each section comprises substantially annular upper and lower horizontal plate members indicated at *a*, *a'* respectively, 80 which are connected by a vertically disposed web having blast openings indicated at *b*, formed therein. The upper plate member of each section extends outwardly beyond said intermediate member of the section, and is provided with a downwardly extending lip *c* as shown. The sections are placed one upon the other so as to form a hollow structure to receive and distribute the air blast and the topmost member is provided with a closed central portion, indicated at *a'*, so that the air blast is forced to escape into the fuel through the blast openings *b*, and beneath the downwardly extending lips *c*. *d* is the blast distribution 90 box carried by the ring *e* which is rigidly and centrally mounted in the ash-pan *f* and is revolved with the latter through the medium of the toothed gear *g*. *h* indicates the helical ribs which are provided on the outside of the blast distribution box *d* and *i* is the blast-pipe which enters the said box through the stuffing box *j*. In the construction of grate shown in the drawing the sections of the grate are so mounted on the 95 distribution box that they are eccentrically disposed with relation to the center line of the producer and to one another, as clearly shown in Fig. 2.

As will be understood, when the grate 100 105 110

is revolved the sections will be moved laterally with respect to each other and to the center line of the producer, so that the fuel will be moved laterally between the sections and the fuel will not be consolidated.

revolves, a lateral displacement is set up in the fuel, which prevents the consolidation of clinkers and at the same time maintains the fuel adjacent to the sections of the grate 5 in a loose condition, thereby assisting the passage of the blast through the fuel.

Claims:

1. A rotary grate for gas producers, comprising a rotary supporting member, and 10 a plurality of superimposed sections of different diameters carried thereby, each section comprising substantially annular upper and lower horizontal plate members, connected by a vertically disposed intermediate 15 member provided with blast outlets, the upper plate member of each section extending outwardly beyond said intermediate member, and being provided with a downwardly extending lip, the upper plate member 20 of the topmost section having a closed central portion forming the top of the grate, and means for supplying air to the interior of said sections.

2. A rotary grate for gas producers, comprising a rotary supporting member, and a 25 plurality of superimposed sections of different diameters carried thereby, each section comprising substantially annular upper and lower horizontal plate members, connected by a vertically disposed intermediate 30 member provided with blast outlets, the upper plate member of each section extending outwardly beyond said intermediate member, and being provided with a downwardly extending lip, the upper plate member 35 of the topmost section having a closed central portion forming the top of the grate, and means for supplying air to the interior of said sections, said sections having their centers arranged eccentrically with respect 40 to each other and the axis of rotation of said supporting member, whereby a lateral displacement of the fuel is effected as the grate is rotated.

HARALD NIELSEN.
FREDERICK DEACON MARSHALL.
